US00D617893S

(12) **United States Design Patent**
Bierman et al.

(10) **Patent No.:** **US D617,893 S**
(45) **Date of Patent:** ** *Jun. 15, 2010

(54) **ACCESS DEVICE**

(75) Inventors: **Steven F. Bierman**, Del Mar, CA (US);
Richard A. Pluth, San Diego, CA (US)

(73) Assignee: **Access Scientific, Inc.**, San Diego, CA (US)

(*) Notice: This patent is subject to a terminal disclaimer.

(**) Term: **14 Years**

(21) Appl. No.: **29/343,774**

(22) Filed: **Sep. 18, 2009**

Related U.S. Application Data

(63) Continuation of application No. 29/305,172, filed on Mar. 14, 2008, now Pat. No. Des. 601,242.

(57) **CLAIM**

The ornamental design for an access device, as shown and described.

DESCRIPTION

FIG. 1 is a front side perspective view of an access device configured in accordance with a preferred embodiment of the present invention;

FIG. 2 is a top view of the access device shown in FIG. 1;

FIG. 3 is a first side view of the access device shown in FIG. 1, the other side being a mirror image of the first side;

FIG. 4 is a bottom view of the access device shown in FIG. 1;

FIG. 5 is a first end view of the access device shown in FIG. 1;

FIG. 6 is a second end view of the access device shown in FIG. 1;

FIG. 7 is a front side perspective view of an access device configured in accordance with another preferred embodiment of the present invention;

FIG. 8 is a top view of the access device shown in FIG. 7;

FIG. 9 is a first side view of the access device shown in FIG. 7, the other side being a mirror image of the first side;

FIG. 10 is a bottom view of the access device shown in FIG. 7;

FIG. 11 is a first end view of the access device shown in FIG. 7; and,

FIG. 12 is a second end view of the access device shown in FIG. 7.

The features shown in broken lines in FIG. 1 depict environmental subject matter only and form no part of the claimed design.

1 Claim, 4 Drawing Sheets
